UNITED STATES PATENT OFFICE.

IRVING R. COWIN, OF CLEVELAND, OHIO, ASSIGNOR OF ONE-HALF TO WILLIAM CARMACK AND ONE-HALF TO F. C. WERK, BOTH OF CLEVELAND, OHIO.

PRESSURE REGULATOR.

Application filed December 23, 1921. Serial No. 524,435.

To all whom it may concern:

Be it known that I, IRVING R. COWIN, a citizen of the United States, residing at Cleveland, in the county of Cuyahoga and 5 State of Ohio, have invented certain new and useful Improvements in Pressure Regulators, of which the following is a specification.

This invention is a pressure regulator 10 particularly adapted and intended for use on gas lines supplying natural and other gas to burners, and has for its object to provide an improved device by means of which a uniform pressure is automatically assured 15 at each point of combustion regardless of the number of burners in use or the variations in pressure in the supply main. A further object of the device is to homogenize the gas or mixture of gases before it is 20 supplied to the burners, giving a uniform mixture of efficient heating quality. The device has been tested and found to be practically successful for the purposes referred to.

In the accompanying drawings Fig. 1 is 25 a side elevation of the regulator. Fig. 2 is a vertical section thereof. Fig. 3 is a similar section at right angles to Fig. 2. Figs. 4, 5 and 6 are sections on the lines 4—4, 5—5 and 6—6 of Fig. 2.

30 The device includes a cylinder 1 having its ends closed by caps 2 which have nipples 3 to receive the inlet pipe 4 at the bottom and outlet pipe 4^a at the top. A nozzle 5 having a screen 6 in the lower part thereof is mounted in the bottom of the cylinder over the inlet pipe 4, and this nozzle is off set to direct the blast of gas against a fan 10 on a shaft 11 supported by a frame 7 and a cross piece 8 thereon, the shaft being 35 mounted in adjustable screw bearings 12.

40 Mounted between the legs of the frame 7 is a ring 13 between which and an angle ring 14 is clamped the lower end of a bellows 15, the ring 13 being fastened to the legs of the 45 frame 7 in any suitable manner. The upper end of the bellows is fastened to the rim of a flanged disk or plate 16 by a ring 17, the disk being free to move up and down in consequence of the variations of pressure there- 50 under. Springs 18 are connected between lugs 19 and 20 on the plate 16 and ring 14 respectively, and these springs resist lifting action of the plate 16. Adjusting screws 21

are threaded through nipples 22 and stuffing boxes 23 on the upper cap of the cylinder, 55 and these screws act to stop the lift of the disk 16 which works to and from the outlet pipe 4^a to vary the opening thereto. In operation, the gas under pressure enters the lower end of the cylinder through the 60 nozzle 5, and causes the fan to rotate which produces a uniform mixture of the gas, and from the fan the gas flows into the bellows and upwardly against the plate 16, and lifts said plate more or less according to the 65 pressure, and as stated this lift varies the effective outlet opening from the cylinder and consequently regulates the pressure at the outlet and insures a uniform supply of gas to the burners. This action results when 70 any burner is opened by automatically varying the size of the passage from the regulator according to the pressure at the inlet. The rate of flow is thereby automatically controlled according to the pressure and the 75 service demands on the main, and has been found very useful in controlling the flow of natural gas where the pressure is often subject to rather wide variations.

I claim:

1. A gas pressure regulator comprising a casing having an inlet at one end and an outlet at the other, a cylindrical bellows supported in the casing between the inlet and the outlet, a plate extending across the end 85 of the bellows nearest the outlet, and springs connected to said plate, the plate being movable according to the pressure in the bellows, toward and from said outlet.

2. A pressure regulator comprising a cas- 90 ing having an inlet at its lower end and an outlet at its upper end, a nozzle in the casing at the inlet, a fan above the nozzle, adapted to be rotated by the blast from the nozzle, and a bellows in the upper part of the casing, 95 said bellows being provided with an upper plate which works toward and from the outlet to vary the flow therethrough, according to variations in the pressure.

In testimony whereof, I do affix my signa- 100 ture in presence of two witnesses.

IRVING R. COWIN.

Witnesses:

JOHN A. BOMMHARDT,
EDWARD J. HOBDAY.
